UNITED STATES PATENT OFFICE.

ADOLPHUS E. DEASON, OF POTEAU, OKLAHOMA, ASSIGNOR OF ONE-FOURTH TO ROBERT S. BRIDGMAN, OF POTEAU, OKLAHOMA.

SAFETY CHECK OR DRAFT CUTTER.

1,069,534.

Specification of Letters Patent.

Patented Aug. 5, 1913.

Application filed March 21, 1913. Serial No. 755,981.

to all whom it may concern:

Be it known that I, ADOLPHUS E. DEASON, a citizen of the United States, residing at Poteau, in the county of Le Flore and State 5 of Oklahoma, have invented new and useful Improvements in Safety Check or Draft Cutters, of which the following is a specification.

This invention relates to a safety check or draft cutter, the object of the invention being to provide a cutter for use in conjunction with a special form of check, draft or other similar negotiable instrument provided with a table for indicating the maximum amount for which the instrument when filled out is valid, whereby the check or other instrument may be marked to indicate its maximum value in a ready and convenient manner and in such a way as to 15 prevent the amount of figures on the check from being raised to a higher valuation.

A further object of the invention is to provide a cutter of the character described having an adjustable cutter blade, whereby 20 the check may be severed from its stub and marked to indicate its maximum value with facility.

In the accompanying drawing, Figure 1 is a view of an open check book showing the 25 cutter in position for use. Fig. 2 is a view of the check and its stub, showing the check cut away to indicate its maximum valuation. Figs. 3 and 4 are end and side views of the 30 cutter. Fig. 5 is a transverse section thereof. Fig. 6 is a detail view of the sliding blade.

Inasmuch as the check and cutter are especially designed for use in connection 35 with each other, I will proceed to describe the construction and mode of use of the check, as well as the mode and use of the cutter.

As shown, the check comprises a body 1 having an ordinary check form printed 40 thereon, with proper spaces for the place, date, number, name of the bank or other institution on which the check is drawn, together with properly designated spaces for the names of the payee and payer, and the 45 amounts expressed in words and figures. The printed matter upon the body may, of course vary to adapt it for use as a draft or other similar instrument. The body 1 is provided with a stub 2, and arranged at the intersection of the body and stub is a 50 table 3 containing valuation amounts, said 55

table constituting a portion along which the check body is designed to be separated from the stub in such manner as to leave a margin expressing in figures the maximum amount for which the check is valid. The 60 stub may contain any suitable arrangement of spaces and printed matter for the entrance of items respecting amounts brought forward, the amount for which the check 65 is drawn, balances, deposits and other matter for keeping a record or memorandum.

The table 3 consists preferably of three rows of numerals. The first or right hand row bears the numerals from 1 to 20, inclusive, reading downward, the numerals 1 to 10 inclusive, being in regular order followed by the numerals 15 and 20. The second row or column of figures runs from 25 to 100, in regular order or progression, each 70 numeral being an advance of 5 over the other. In the third row or column at the left hand side of the table the numerals run from 200 to 1000 in arbitrary arrangement, such as may be found most convenient under 75 different conditions of service. Of course the arrangement of the numerals in the rows and their values may be changed at will according to the character and extent in valuation figures which it is designed to have the 80 valuation column adapted to express from minimum to maximum. The columns of figure receiving spaces, said lines being the figures therein are separated into transverse rows by transverse lines, forming 85 figure receiving spaces, said lines being preferably inclined at a suitable angle in a direction toward the bottom edge of the 90 body of the check.

The cutter comprises a holder 4 preferably consisting of a single piece of metal bent upon itself to provide superposed plates or leaves 5 and 6. The lower leaf 6 may be of somewhat greater length than the upper leaf 5 and have its end portions bent downwardly to provide guide or stop flanges 7 to engage the upper and lower edges of the stub 2, when the cutter is used in connection with checks or drafts bound singly in book form. The upper leaf 5 is also of somewhat 100 less width than the lower leaf 6, whereby the latter is provided with a projecting severing edge 8. The leaves form an intervening guideway 9 for a cutter blade 10. This blade is provided at its left hand 105 edge with a guide flange 11 movable in a guide groove 12 formed by stamping

up a portion of the leaf 5, whereby said blade is guided positively in its movements and held from outward lateral displacement. The inner half of the blade, 5 measuring from its longitudinal center, is slidable on the leaf or plate 6, said plate having its outer half projecting laterally beyond the edge 8. The said outer half of the blade is offset downward to lie substantially 10 in the plane of the edge 8, whereby the guiding surface 13 is provided for engagement with said edge 8, insuring proper movement of the sliding cutter in a determined path. At one, its lower, edge, the cutter is provided 15 with a stop flange 14 to limit its upward movement, which flange terminates at its inner edge from the edge of the flange 11, so that one and the same blade may be used in conjunction with two or more alined holders 20 and be moved in guided connection between the same. In practice, where a single holder is used, this holder may be of a length corresponding to the length of the stub or depth of the table 3, as in the use of the 25 cutter with checks bound singly in book form, but where each page of the check or draft book is printed to provide several checks and corresponding stubs, the holder and blade may be enlarged correspondingly 30 or by using two or more holders the blade may be adjusted from one to the other for continuous use in separating two or more checks at a time from the book. The upper edge of the blade is provided with a V- 35 shaped notch or recess 15 intersecting the guide surface 13 and permitting of the ready bending of the blade in forming the same. The outer half of the edge of the upper blade is cut away on an incline to provide a 40 cutting surface 16 adapted for coöperation with the severing edge 8, and in the use of which the notch 15 permits of the ready severance of the paper on two different lines, at an angle to each other.

45 In the use of the cutter for severing the filled out check and simultaneously expressing the maximum amount for which the check is valid, the holder is arranged as shown in Fig. 1 so as to bring the edge 8 along the 50 left hand column in which the maximum value figure is located and the blade is adjusted until it alines with the inclined transverse line beneath such figure. By then 55 grasping the body of the check and drawing the same downward and forward the check may be severed from the stub along the exposed portion of the edge 8, the surface 16 and the longitudinal outer edge of the cutter blade, as will be readily understood, leaving 60 a portion of the table intact therewith, the maximum value figure of which will indicate the maximum value in dollars for which the check is valid. It will be understood, of

course, that the adjustability of the blade adapts it to be arranged to bring its edge 16 below any particular numeral in any particular one of the columns, thus enabling the check to be severed from the stub with ease and facility.

By employing a check or draft and a cutter of the character described the check may be provided with an ineradicable maximum value indicating device, without the necessity of employing complex auxiliary marking devices in order to indicate upon the 75 check its maximum value, and an equal degree of safety may be secured.

If desired, and as shown, the check body may be provided with suitable warning matter to indicate that it is valid only under 80 certain conditions. In the present instance at the top of the check is printed the following warning "This check will not be paid unless figures show in margin," while the following is printed at the bottom of the 85 check, "Not good for more than indicated by figures in margin on the left." These warning notices may, of course, be worded in any suitable manner desired.

I claim:—

1. A cutter of the character described comprising a piece of material bent to form superposed plates provided with a guideway, the lower plate having a projecting severing edge and the upper plate a guide groove, and a cutting blade slideable between and in contact with said plates and provided with a flange engaging said groove, said blade having a longitudinal severing edge projecting beyond the severing edge of the 95 holder and an oblique transverse cutting edge extending on a line intersecting said severing edge.

2. A cutter of the character described comprising a holder formed of a folded 100 piece of material providing upper and lower plates, the lower plate having a projecting severing edge and the upper plate a guide groove, and a cutter movable on one side of its longitudinal center between said plates 110 and having a flange engaging said groove, an offset on the opposite side of its longitudinal center into the plane of the bottom plate, said offset portion of the blade being provided with a longitudinal severing edge, 115 a stop member at one end and an oblique cutting edge at its opposite end, said oblique cutting edge being arranged on a line intersecting the severing edges of the holder and blade.

In testimony whereof I affix my signature in presence of two witnesses.

ADOLPHUS E. DEASON.
